UNITED STATES PATENT OFFICE

EDWARD L. HESSEL, OF MINNEAPOLIS, MINNESOTA, ASSIGNEE TO LITTLE GIANT MANUFACTURING CO., OF MINNEAPOLIS, MINNESOTA, A CORPORATION OF DELAWARE

RADIATOR HANGER

Application filed January 20, 1928. Serial No. 248,103.

This invention relates to improvements in radiator hangers and has for a particular object to provide a simplified hanger construction in which the tie bolt, for holding the 5 radiator in upright position upon the hanger, is connected directly with the hanger, rather than with a wall bracket which is ordinarily used to support the hanger.

Other objects of the invention are to provide means in the form of an abutment by which the hanger is supported, and adjusted and to provide a tie bolt connection between this adjusting and supporting means by which the tie bolt is directly connected to the 25 hanger and by which the adjusting means is held against accidental movement after adjustment; to provide an arrangement whereby the tie bolt may be dropped downwardly into connecting position; to provide a hanger having a socket in its upper end into which a projection of the tie bolt may be dropped to secure the tie bolt directly to the hanger; and generally to provide constructions that eliminate the use of means upon the wall bracket 25 which supports the hanger, to provide adjustment for the tie bolt according to the adjustments of the radiator in directions parallel with the wall.

Features of the invention include the broad idea of connecting the tie bolt directly with the hanger rather than with the wall plate, as well as to the arrangement of the parts, and details of construction of the parts per se, all as shown in the drawings and described in the 35 specification.

Advantages and uses of the invention will be set forth in the description of the drawings forming a part of this application, and in said drawings:

40 Figure 1 is a top plan view showing one form of the invention in use, a portion of the radiator being broken away to show the abutting engagement of one abutment of the tie bolt therewith;

45 Figure 2 is a vertical section of the construction of Figure 1;

Figure 3 is a front view, with the radiator removed, and showing the tie bolt in section;

50 Figure 4 is a view of the recessed and

threaded hanger supporting abutment, which also functions as a means for adjusting the hanger in a vertical direction;

Figure 5 is a plan view of a modification, in which the upper end of the hanger is recessed to receive a projecting portion of the tie bolt; 55

Figure 6 is a vertical section thereof;

Figure 7 shows a detail of one form or 60 projecting portion for the tie bolt;

Figure 8 is a vertical section showing another form in which the hanger is provided with a removable extension recessed to receive the tie bolt; and

Figure 9 is a perspective view of the removable extension of the hanger, which differs in form from that shown in Figure 2. 65

Referring first to Figures 1, 2, 3 and 4. A bracket or wall plate having a wall-engaging portion 1 is secured against the wall, in this instance by a single bolt 2, passing through a suitable opening in the plate. The portion 1 is provided with a prong 3 which enters the wall and prevents rotative motion of the bracket upon the bolt. The bracket has a 70 horizontal portion 5 having a slot 6 therein elongated in a direction parallel with the wall, to allow adjustment of the hanger in that direction. The wall bracket simply provides a support for the hanger and allows adjustment of the hanger in a direction parallel with the wall. A preferred construction of 75 the hanger is shown, although no intention is had to be limited to the particular construction. The hanger should be considered as an 80 element attachable to the wall plate and having means for supporting a radiator. In this instance, the hanger comprises a rod 10 threaded at upper and lower ends respectively as at 11—12. It will be understood that the 85 threads may be of any length so that any desired degree of vertical adjustment may be had. In this instance, the lower end of the hanger has rotatably connected therewith a foot 13 having a curved portion 14 to engage 90 the connecting element 15 of the radiator and having a flattened rear portion 16 which engages the wall. A nut 17 cooperating with the threads 12 provides means for vertically 95 adjusting the foot 13. The upper end of the 100

rod extends loosely through the slot 6, and the threads 11 have engaged therewith an element 20 which acts as a combined hanger-supporting, hanger-adjusting, and tie-bolt-connecting element, thus adapted to perform at least three functions. This element is provided as shown in Figure 4 with an upstanding portion 21 centrally slotted as at 22, with the slot opening upwardly. The abutment 20 is thus provided with a recess to receive the shank of a tie bolt and to abuttingly engage an abutment of the bolt to prevent bolt translation in a horizontal, axial direction. The tie bolt is indicated at 25 and in this instance, has a head 26 engaged with an abutment clip 27, although it will be understood that the abutment which engages the radiator as shown in Figure 1 may be formed in any preferred manner. No claim is made for the particular construction of this element except that it is provided with two abutments one of which must engage the radiator in the manner shown in Figure 1 and the other of which must be capable of engaging the rear surface 29 of the upstanding portion 21 of the adjustable abutment 20. The engagement of the abutments is such that the movement of the radiator away from the rod or hanger is prevented. It will be noted that when the tie bolt 25 has its abutments engaged as set forth, the rotation of the adjusting-abutment 20 is prevented. This arrangement is an important feature of the invention, and is broadly claimed, along with direct attachment of the tie bolt with the hanger, instead of with the wall plate. An important result obtained by having the tie bolt directly connected for movement with the hanger is that it is unnecessary to provide means upon the bracket to receive the tie bolt for each adjusted position of the radiator in a direction parallel with the wall. It will be further noted that the tie bolt engages the radiator and is detachably connected with the bracket. It will further be noted that it is detachably connected at a point above the bracket, and that it can be dropped into position within a recess carried by or as part of the hanger. As best shown in the modification in Figure 6 the hanger 10^a has a recess 30 in its upper end and the tie bolt 25^a has an extension 31 which fits into the recess. The tie bolt in this case has the same general construction as the first mentioned tie bolt, except that one of the abutments is the extension 31, secured by the nut 28^a, although it will be understood that element 31 may be integral with the tie bolt. In this case the nut 28^a engages the extension abutment 31. It will be noted that the abutment 31 may be dropped into the recess 30 from above. A nut 32 is employed to support the hanger 10^a, and this nut 32 has threaded engagement with the hanger in a manner similar to that shown for the abutment 20. The extension 31, as

will be seen in Figure 7, in this instance has an opening 33 through which the shank of the bolt 25^a passes. The extension is tapered as at 34 so that downward movement in the recess 30 will be limited, but so that the element 25^a, and the extension 31 can be raised and lowered within the socket 30.

In the modification of the invention shown in Figure 8, the hanger 10^b traverses the bracket in the same manner, but the hanger is provided with a removable and recessed extension generally indicated at 35 which does not have a threaded engagement with the rod. This extension, as a bracket, has an opening 36 through which the upper end of the hanger passes, and the recess is provided in this instance in the upstanding portion 37, the recess being indicated at 38. The recess is formed in this instance in substantially the same manner as shown in Figure 4 for the first form of the invention. The tie bolt 25^b is connected with the removable extension 35 in the manner similar to the connection of the bolt in the other forms. In this instance, however, the nut 32^a connects with the hanger 10^b at the upper side of the horizontal portion of the extension 35, and the nut bears downwardly onto the extension and thus compressively secures it against the upper surface of the horizontal portion of the wall bracket.

I claim as my invention:

A bracket, a hanger including a rod, a nut securing the rod, said nut having a recess into which a bolt shank can be dropped, said recess including a pocket within which a nut threaded on the bolt, is received when the bolt is translated outwardly and when so received is prevented from rotation when the bolt is rotated.

In witness whereof, I have hereunto set my hand this 13th day of January, 1928.

EDWARD L. HESSEL.
